8 Claims. (CL. 171—119)

This invention relates to selecting tuning apparatus for either wire or wireless telephone or telegraph circuits.

The object of the invention is the provision of
5 a compact and easily adjusted equipment by
means of which the receiving equipment may be
made responsive only to the oscillations of a defi-
nite frequency and emanating from a certain
selected sending station.
10 One of the features of the invention resides in
the provision of a plurality of coils or loops of
insulated conductor, the loops being mounted one
within another and so arranged that the loops
may all lie in substantially the same plane or
15 they may be rotated or translated one within the
other, so that the planes of the inner loops may
be placed at various angles to the planes of the
outer loops. The coils may be all connected in
series or parallel, or certain coils may be only
20 inductively related to the others depending on
the circuit with which the device is used.

Another feature consists in mounting the loud
speaker within the center of the innermost coil.

Another feature of the invention resides in the
25 provision of means whereby the rotation of one
of the coils will automatically cause a rotation of
a second coil relative to the first.

A still further feature resides in additional
means whereby the inner coils may be adjusted
30 relative to each other and to the outer coil.

A still further feature resides in the provision
of a metal sheet or plate adjacent to the coil
which may be adjusted relative thereto in order
to effect a tuning operation.

35 Other features and advantages will appear as
the description of the invention progresses.

In the present disclosure three coils of wire are
shown of sizes such that the second coil may be
readily mounted within the first and the third
40 within the second. The three coils may comprise
various numbers of turns and the different ar-
rangements will vary as to the total length of wire
included in the coils. While the three coil ar-
rangement shown in the drawings has been found
45 to give very good results, a two coil structure
will be found satisfactory for some purposes and
for very fine tuning more than three coils may be
found desirable.

The coils of the present invention may be used
50 to take the place of the usual antenna or they may
be placed in series with the usual antenna, or a
portion may be connected to the antenna and
the remaining portion connected to the receiving
equipment in various ways. By mounting the
55 coils about and within the horn, the receiving

equipment may be constructed as a self-contained
unit and therefore may be moved from place to
place without bothering with antenna connec-
tions.

It is believed the invention will be most readily 5
understood from a detailed description thereof,
taken in connection with the accompanying
drawings, in which—

Fig. 1 is a side view partly in section of one
form of applicant's apparatus comprising three 10
coils nested respectively one within the other;

Fig. 2 is a view of the form of the device shown
in Fig. 1, with the inner coils adjusted in relation
to the outer coil;

Fig. 3 is another view of the same apparatus but 15
shows each of the coils arranged in a plane at
right angles to each of the other two coils;

Fig. 4 is a side view of a modified form of the
device in which the conductors forming the sev-
eral loops are arranged in the same plane instead 20
of side by side as in the device of Fig. 1;

Fig. 5 is a view of the device such as shown in
Figs. 1, 2, and 3 but illustrates the manner of
mounting the loud speaker upon and within the
innermost coil; 25

Fig. 6 shows another modified form of the de-
vice in which the conductors forming a coil are
arranged in zig-zag manner and simplify the re-
quired supporting framework;

Fig. 7 is a cross section on the line 7—7 of the 30
device, shown in Fig. 6;

Fig. 8 is a plan view of the arrangement of Fig.
1, but shows in addition the manner of adjustably
mounting the metal sheet or plate in relation
thereto; 35

Fig. 9 is a transverse sectional view through the
device such as is shown in Fig. 5, but modified to
illustrate a double diaphragm loud speaker with-
in the innermost of the three coils;

Fig. 10 is a section on the line 10—10 in Fig. 1; 40

Fig. 11 is a section through the rim of either the
outermost or the second coil of the device of Fig.
1, illustrating the manner in which the actuating
cord or belt passes over the idler pulleys;

Fig. 12 is a view partly in section of a modified
form of the device shown in Fig. 1, whereby the
inner coils may be adjusted in relation to the
outer coil; 45

Fig. 13 is another modification of the arrange-
ment shown in Fig. 1, and is adapted to cooperate
with the structure shown in Fig. 12 to obtain the
result referred to; 50

Fig. 14 is a schematic diagram of the circuits
which have been found to be satisfactory when
used with the device of Fig. 1; 55

Fig. 15 illustrates diagrammatically circuits which have been found satisfactory with the form of the device shown in Fig. 4;

Fig. 16 shows a still further circuit arrangement;

Fig. 17 shows a modified form of coil; and
Fig. 18 is a perspective view of a modified form.

Referring now to the drawings in which like reference characters indicate like parts in the several views, 10 is an annular ring somewhat T shaped in cross section, as shown in Fig. 10. The ring 10 is supported by and fixed to the column 11 which, in turn, is pivotally supported on the rod 12, the lower end of which is fixed to the base 13 in any desired manner. Extending laterally from the column 11 and fixed thereto is a handle 14 by means of which the ring or hoop 10 may be rotated about the rod 12 as an axis.

Mounted within the ring 10, and preferably concentrically therewith, is a second ring 15 similar to ring 10 but smaller in size, and mounted within the ring 15 is a third ring 16 of similar formation. The ring 15 is provided at one side thereof with the friction collar 17 within which projects the end of the pin 18 rotatably supporting the ring 15. On the opposite end of the pin 18 is a pulley 19 over which passes the cord or belt 20. The cord 20 will preferably make one complete turn about the pulley 19 so as to avoid slipping thereon. Fixed to the upper end of the rod 12 is a pulley or belt wheel 21 about which passes the opposite end of the loop formed by the cord or belt 20. The cord 20 passes over the idler pulleys 22 to prevent frictional engagement of the cord with the ring 10. The idler pulleys 22 are preferably mounted in recesses 23, in the stem 24 of the ring 10, as shown in Fig. 10, and strips of veneer or other thin material 25 are preferably secured to the side of the stem 24 in order to provide a finished external appearance.

Positioned within the ring 10, diametrically opposite the pin 18, is a pivot or pivot member 26. The inner end of the pin 26 is loosely received within the ring 15 and is provided with a pulley 27 or belt wheel 27 fixed thereto, and passing about the pulley 27 is a cord or belt 28 which is similar in structure and function to the belt or cord 20. Mounted within the innermost ring 16 are the pivot pins 29 and 30. Pin 29 is loosely received by the ring 15 but has rigidly fixed thereto the pulley or belt wheel 31 about which passes the cord or belt 18. Idler pulleys 32 are provided for a purpose similar to the idler pulleys 22.

From an inspection of the structure thus far described, it will be noted that when the outmost ring 10 is rotated by means of handle 14, one lap of the cord 20 tends to wind up on the pulley 21 thus causing the pulley 19 to rotate, which in turn rotates pin 18 and causes the rotation of the second ring 15 relative to ring 10. In like manner, as the ring 15 rotates one lap of the cord 28 tends to wind up on the fixed pulley 27 thus causing the pulley 31 to rotate and consequently producing a rotation of the innermost ring 16.

Fig. 2 shows the rings in process of being rotated and Fig. 3 shows the three rings rotated to positions such that each occupies a plane at right angles to each of the other two. It will thus be seen that whenever the outer ring is rotated, the inner rings will rotate in unison therewith until a position is reached such as indicated in Fig. 3.

After the coils have been adjusted by rotation of the column 11, as above described, the coils 5 may be further independently adjusted in rela-

tion to each other by moving each separately by the hand of the operator. The pivot pins 18, 26, 29 and 30 are mounted in friction sleeves, such as sleeve 17, to permit this independent adjustment.

Wound about the flange 33 of the outer ring 10 (see Fig. 10) is a coil 34 of wire. This coil 34 comprises only the turns shown at the left hand half of Fig. 10. The conductor then passes inwardly adjacent to pivot pin 26 to the middle ring 15 on which it is wound as indicated at 35 in Fig. 3. Again it is to be understood that coil 35 comprises only the turns on the lower half of ring 15, as seen in Fig. 3. After making several turns about ring 15, the conductor passes adjacent to the pivot pin 29 to the innermost ring 16 and is given several turns about the circumference of ring 16, as indicated at 36 in Fig. 3. When a sufficient number of turns have been made about the ring 16 the conductor is secured to the ring and is then looped back on itself and a similar number of turns are made about the circumference of ring 16 in the opposite direction as shown at 37. The conductor then passes out adjacent to the pin 30 and is wound about ring 15 a number of turns, as shown at 38, it being understood, however, that the coil 38 is wound in the opposite direction to coil 35. Finally the conductor passes adjacent to the pivot pin 17 and is given a number of turns about the circumference of ring 10 as shown at 39 in Fig. 10. It will be understood that the turns of the coil 39 are in the opposite direction to those of the coil 34. The ends of the conductor will preferably be secured to binding posts on the column 11 (not shown).

It will thus be seen that starting from the outside, a number of turns are made about the ring 10, then a number about the ring 15 in the same direction, then a number of turns about the ring 16 in the same direction. The conductor is then doubled back on itself and similar coils are made on the rings 16, 15 and 10, all being wound in the opposite direction to the coils first placed thereon.

The structure shown in Fig. 4 may be similar to that of Figs. 1, 2, and 3, except the turns of the wire forming the coils are all in substantially the same plane. The outer frame 40 is carried by the column 41. The second frame 42 is pivotally supported from the frame 40 by means of the pivot pins 43 and the innermost frame 44 is pivotally supported from frame 42 by means of the pivot pins 45.

Taking the structure as shown in Fig. 4, the conductor is carried first around frame 40 adjacent to the outside slat 46 and thence around and around, each turn being inside the other in series relation. Each of the three coils shown in Fig. 4, is wound in a like manner and the conductor presents a substantially continuous helical like arrangement from the outside to the center, all the turns being in the same direction. The direction of the winding of any coil to the other, however, may be changed by rotating the frame carrying it through 180 degrees. In Fig. 5, the device of Fig. 1 is shown with a supporting member 47 mounted on the ring 16, a loud speaker 48, or other similar device, being carried by the supporting member 47 adjacent to the center of the ring.

The structure shown in Figs. 6 and 7 comprises the three annular rings 50, 51, and 52 of different diameters, ring 51 being positioned within 50, and 52 within 51. Coils 53, 54 and 55 carried by the rings 50, 51, and 52, respectively, are 75

formed of comparatively straight portions of heavy wire arranged in intersecting relation and are self-supporting except that they are secured to the rings 50, 51, and 52.

Fig. 8 shows the device of Figs. 1, 2, and 3 with a metal sheet or screen adjustably mounted adjacent to the coil. The ring 10 has secured to the top thereof, by means of the pin 60, an arm 61. Slidably mounted on the arm 61 is a sleeve 62 from which is suspended a sheet metal reflector or screen 63. The screen 63 is preferably joined to the sleeve 62 so as to permit rotation to various vertical planes. Due to the pivotal arrangement of the arm 61 and slidably mounted sleeve 62 and the pivotal connection of plate 63 to the sleeve 62, the plate 63 may be moved into various relations to the coils.

Fig. 9 indicates a manner in which double diaphragm push and pull loud speaker may be mounted in the center of the innermost coil. The diaphragms 64 and 65 are secured to the innermost ring and have mounted therebetween, in any desired manner, the electro-magnets 66 by which the diaphragms are operated. If desired, outwardly fixed flanges 67 and 68 may be provided on opposite sides of the ring 16 in the nature of abbreviated horns. It is to be understood that the loud speaker and horn arrangement disclosed will in no way affect the rotation 30 of the ring 16 within ring 15.

In Figs. 12 and 13 is shown means for separately adjusting the inner coils in relation to the outer and in relation to each other. It is to be understood that the modification shown in Fig. 35 12 will be positioned at the point occupied by the pivot pin 26 of Fig. 1, and that one of the pulleys in Fig. 12 will be positioned at the point occupied by the pivot pin 26 of Fig. 1, and that one of the pulleys in Fig. 12 will have the same 40 function as pulley 27 in Fig. 1. This figure shows the outer ring 10a, and the next inner ring 15a, which will be the same as above described in connection with Fig. 1, except as to the modification of the operating means. Fixed within 45 the ring 10a is one end of a sleeve 70, the opposite end of which is loosely received by the outer flange of the ring 15a. Rotatably mounted within sleeve 70 and the rings 10a, and 15a, is a sleeve or collar 71 through which extends the 50 adjustable shift pin or plunger 72. The pin 72 is provided with the knob or hand hold 73 by means of which it may be moved inwardly or outwardly to the shift operative connections such as will subsequently appear.

55 Rotatably mounted upon the sleeve 71 and within the recess 74 in the ring 10a, is a pulley or wheel 75. In a similar manner the pulleys 76 and 77 are rotatably mounted upon the sleeve 71 within the recess 77 in ring 15a. It may be 60 here explained that the pulley 76 of Fig. 12 has, in certain stages of the device, exactly the same function as pulley 27 of Fig. 1 and will be joined to a pulley carried by the middle ring 15a which will be in all respects similar to the pulley 31 of Fig. 1.

The sleeve 71 is provided with a pair of slots 78 and 79 and the plunger 72 is provided with a corresponding pair of lugs 80 and 81 adapted to slide in the slots 78 and 79, respectively. The 70 pulleys 75, 76 and 77 have their inner surfaces which are positioned about the sleeve 71 fluted or provided with a series of notches into any one of which lugs 80 or 81, as the case may be, may be positioned. The right end of the sleeve 70 is also provided with notches or recesses 83 into

which the lug 81 on the plunger 72 may be positioned.

From an inspection of the drawings, it will be noted that the lug 80 projects into a notch in the pulley 75 and the lug 81 extends beyond pulley 77 into the frame of ring 15a, locking it to the sleeve 71. Thus it will be seen that when the plunger 72 is pushed into its extreme right hand position, as viewed in Fig. 12, pulley 75 and ring 15a will both be locked to the sleeve 71.

If the plunger 72 be moved to the left to its intermediate position, lug 80 will still be in engagement with pulley 75 while lug 81 will have moved into engagement with pulley 77. Therefore in this position, pulleys 75 and 77 will be 15 locked to sleeve 71.

If now the plunger 72 is moved to its extreme left hand position, lug 80 passes out of engagement with pulley 75 and lug 81 becomes positioned in a notch 83 of the fixed collar 76, thus locking 20 pulley 76 in fixed position and leaving pulley 75 free to rotate about collar 71. The manner in which these several pulleys function will be described after the structure shown in Fig. 13 has 25 been described.

Referring now to Fig. 13, a base 13a is shown, to which is secured rod 12a, in the same manner as rod 12 in Fig. 1. Fixed to the rod 12a, as by means of a spline 84, is a pulley 21a, which has the same function as the pulley 21 in Fig. 1. The 30 pulley 21a will be joined by a cord or belt 20a, to a pulley such as the pulley 21, Fig. 1. Positioned above the rod 12a, and rotatable within the stand or column 11a, is a sleeve 85 to the lower end of which is fixed, in any desired manner, the disc 86 having projecting arm 87 by means of which the sleeve 85 may be rotated. Fixed to the upper end of the sleeve 85, in any desired manner, is a pulley 88.

Pulley 88 of Fig. 13 is joined to pulley 75 of 40 Fig. 12 by a cord or belt 89 in the same manner that pulley 31 is joined to pulley 27 by the cord 28 in Fig. 1. Thus when the handle 87 is rotated, sleeve 85 and pulley 86 also rotate and the belt 89 causes pulley 75 to rotate as previously described. However, pulley 75 may be either fixed 45 to sleeve 71 or free to revolve thereon, depending on the position of plunger 72.

The operation of the modification shown in 50 Figs. 12 and 13 will now be described. Assuming that the plunger 72 is moved to its extreme left hand position, the operation will be substantially identical with that above described in connection with Fig. 1. Thus when the column 11a is rotated by means of the handle 90, the cord 20a 55 will wind up on pulley 21a and cause a rotation of the pulley corresponding to 19 in Fig. 1, thus rotating the ring 15a within ring 10a. It will be recalled that when plunger 72 is at its extreme left position, pulley 76 is locked to fixed sleeve 60 70. Therefore as the ring 15a rotates, the cord or belt 91 will wind up on pulley 76 and, acting on a pulley such as 31 of Fig. 1, will cause the innermost ring to be rotated. The rotary operation of the coils thus far described may be for 65 the purpose of tuning in roughly the desired station or other like purpose.

When it is desired to adjust the inner coils relatively to the outer one independently of the means which causes the coils to rotate in unison, 70 handle 87 is operated to rotate sleeve 85 and consequently pulley 88. Assuming that the plunger 72 is in its middle position, pulley 77 will now be locked to sleeve 71, thus, as the pulley 88 rotates, the movement thereof will be trans- 75

mitted through cord 89 to pulley 75 which will act to rotate the sleeve 78 and consequently pulley 71. Pulley 71 will be joined by a cord or belt to a pulley carried by the upper end of a pivot pin such as 29, of Fig. 1. Thus when the shift plunger 72 is in intermediate position, the rotation of collar 85 will effect the movement of the innermost coil relative to the other two.

When the plunger 72 is moved to its innermost position, pulley 75 and the ring 15a will be locked to the sleeve 71. Thus, if the sleeve 85 be now rotated, the middle coil will rotate within the outer coil 10a.

Referring now to Fig. 14, an attempt has been made to show the three coils, each divided into two parts wound in opposite directions. Starting from the conductor 95 which is joined to the antenna, the wire is wound in a counter-clockwise direction about the outermost ring, then passes inwardly as indicated at 96 to the middle ring about which it is wound in the same direction and thence it passes inwardly as indicated at 97 to the innermost ring about which it is wound in the same direction. The wire is now doubled back as indicated at 98 and is wound about each of the three rings in a similar manner but in the opposite direction. The terminal of the wire 99 is associated with the receiver in any of the many well known manners. The device has been found to give very satisfactory results with the point 78 connected to ground. Good results have also been obtained when no ground connection was supplied to 98. As a matter of fact, the tuning arrangement just described has been found to give very satisfactory results when connected into the receiving circuits in many different manners.

In Fig. 15, the three coils of the device are shown connected in series, one end of the conductor being joined to the antenna 100 and the other end 101 being joined to the receiver.

In Fig. 16, a still further circuit arrangement is described. In this arrangement one coil 102 has one of its ends joined to the antenna 103, the other end 104 being open. Another coil 105 has its end 106 grounded, the opposite end 107 being open. The third coil 108 has its opposite ends joined to the coil 109 which is inductively associated with the receiver. Under certain circumstances, the open ends of coils 102 and 105 may be joined together advantageously.

In Fig. 17, there is shown a conductor 110 comprising insulated wire wound in spiral formation about a flexible member 111. The flexible member 111 may be either a cord or of conducting material, as a wire. The conductor thus formed may be wound about the rings heretofore described to form a coil of spirally arranged wire, as indicated at 112. Where the wire is employed for the flexible member 111, the member 111 may under certain circumstances be used as the secondary, the wire spirally arranged thereabout, acting as the primary.

It has been found that when a structure employing a plurality of coils of wire, such as herein disclosed, is rotated, it acts to change the frequency of the circuit and thus stations may be tuned in and tuned out by rotating the coil structure as a unit without rotating them in relation to each other. For instance, if a structure such as found in Fig. 1, but having the driving pulley arrangement omitted, is rotated, the sending stations of the surrounding territory will be brought in one after another and then tuned out. Assuming now a station has been brought in by ro-

tating the coils as just described, it is quite likely that other stations will also be audible. If now the several coils are adjusted in relation to each other, a point of adjustment will be found wherein in all except the desired station will be tuned out. Thus the device herein disclosed may be employed without use of the pulley operating means. However, under certain circumstances, tuning may be more advantageously affected by rotating the coils in unison as described in connection with Fig. 1. Having tuned in the desired station by the arrangement shown in Fig. 1, the final adjustment of the coils in relation to each other may be brought about by the means shown in Figs. 12 and 13. While in connection with the several circuit diagrams, one of the coils has been described as connected to the antenna, the arrangement has been found to give very satisfactory results where no antenna is employed, it being used both as an antenna and as a tuning device.

It will be noted that as the coils are rotated they not only change their inductive relation to each other, but also change the relation of the planes of the coils to the point from which the electrical oscillations emanate. It is thought that this feature of changing the relation of the plane of the coil to the direction from which the oscillation originates has a material effect on the tuning operation. Furthermore, if one of the inner coils is rotated through an angle of 180 degrees, its relation to the other coils is reversed. There are a large number of ways in which the coils herein disclosed may be adjusted in relation to each other and connected to a receiving circuit.

Referring now to Fig. 8, the operation of the shield or screen 63 will be described. It has been found that after the coils have been rotated so as to bring in the desired sending station, a very material tuning effect will be produced by adjusting the relation of a metal plate, such as shown on 63, to the coils. This plate 63 may be grounded or merely suspended in insulated relation. The plate 63 perhaps affects the capacity of the circuits and it is thought it likewise may have a shield effect. The experiments with the plate 63 have not been carried to the point where the theory of its effect is clearly understood. However, it has been absolutely determined that it does have a very material tuning effect. In many cases the shield acts not only to eliminate the undesired station, but seems to cause amplification of the oscillations received from the desired station. The shield may be used when rotating the coils as a unit to bring in the desired station and also to effect a tuning operation when the coils have been rotated in relation to each other.

It will be noted that the arrangement of Fig. 5 shows the column 11 joined to the base through the medium of a pivot joint 115 which may be held in locked position by means of a butterfly nut 116. This permits the coils to be tilted as well as rotated.

One method of rotating the coils is shown in the drawings but many other ways may be readily designed. For instance, a small flexible shaft and crown gears may be substituted for the pulley and cord arrangement. Also by properly arranging the pulleys and anti-friction rollers, a single continuous cord or belt may be employed.

The coils may be used in many different circuit arrangements. The coils may be arranged in series, parallel or series parallel and either electrically or inductively related. Also for certain

tuning operations it may be found desirable to take off taps from certain points of the coils which may be carried to a circuit controlling device separate from the coil structure.

5 Instead of providing a small flat base, as shown in the drawings, a base having a cavity or recess therein may be provided, the recess being employed to receive the tubes and other parts of the equipment.

10 The coils shown herein may readily be employed to take the place of the present antenna coils.

15 Fig. 18 is a perspective view of a modified form of the apparatus, in which the wires of the coils are supported by two separated annular members 117 connected by cross members 118 and having tubular axial members 119 containing wires leading to the various coils. A switchboard 120 is mounted on the base and provided with sockets 20 121 and plugs 122 carried by wires 123. The sockets 121 have their wires connected to different parts or sections of the outer coil. By this arrangement connection may be made to the outer coil, so that either the whole or any part of this 25 coil may be connected in circuit.

While in the drawings and in the above specification, certain forms of the invention have been specifically disclosed, it is to be understood that many other modifications of the device are contemplated by the inventor and the invention should therefore be limited only by the scope of the appended claims.

30 This application is a substitute for application Serial Number 46,692, filed July 29, 1925 (renewed March 25, 1933), Selective receiving apparatus for wireless telephone or telegraph set.

35 Having thus described my invention, what is claimed as new and is desired to be secured by Letters Patent of the United States is:—

40 1. In radio apparatus, a base, a coil and means for rotatably mounting said coil on said base, a second coil within said first mentioned coil, means carried by said first coil for supporting said second coil in pivotal relation thereto, a 45 third coil within the second coil and means on said second coil for pivotally supporting said third coil, and means interconnecting said coils whereby they may be rotated in unison each in relation to the other.

50 2. In radio apparatus, a coil and means for pivotally supporting the same, a second coil within said first mentioned coil, each of said coils com-

prising two parts wound in opposite directions, and means carried by said first mentioned coil for supporting said second coil in pivotal relation thereto.

3. In radio apparatus, a coil and means for pivotally supporting the same, a second coil within said first mentioned coil for supporting said second coil in pivotal relation thereto, and a third coil within the second coil and means for pivotally mounting said third coil on said second coil, each of said coils comprising two parts wound in opposite directions. 10

4. In a radio apparatus, a supporting base, a coil supported by said base, an inner coil supported by said first mentioned coil, shaft and pulley means located in said base and said coils, for rotating said coils in relation to each other and to said base. 15

5. In a radio apparatus, a supporting base, a coil directly supported by said base, a coil supported by said first mentioned coil, means in said base and said coils for rotating said coils in relation to each other, control means in said base for operating said first mentioned means, said coils having interlocking means for holding them stationary with respect to each other when said control means is applied. 20 25

6. In a radio apparatus, a base, a coil pivoted on said base, a second coil pivotally mounted on said first coil, a third coil pivotally mounted on said second coil, and operating means mounted on said base for bringing about turning movement of all of said coils. 30

7. In a radio apparatus, a base, a coil pivoted on said base, a second coil pivotally mounted on said first coil, a third coil pivotally mounted on said second coil, and operating means mounted on said base for bringing about relative movement between said coils. 35

8. In a radio apparatus, a base, a coil pivotally mounted on said base for turning movement in one plane, a second coil pivoted on said first coil for turning movement in a plane at right angles to the plane of the first coil, a third coil pivoted on said second coil for rotation in a plane at 45 right angles to the plane of rotation of said other coils and operating means mounted on said base for bringing about turning movement of each of the coils relative to the other in their respective planes of rotation. 50

HARRY PRESTON PRATT.
